(57) **CLAIM**

The ornamental design for a low bay luminaire, as shown and
described.

DESCRIPTION

FIG. 1 is a top perspective view of a low bay luminaire
according to the present invention.

FIG. 2 is a bottom perspective view of the low bay luminaire
illustrated in FIG. 1.

FIG. 3 is a top plan view of the low bay luminaire illustrated
in FIG. 1.

FIG. 4 is a front elevation view of the low bay luminaire
illustrated in FIG. 1.

FIG. 5 is a side elevation view of the low bay luminaire
illustrated in FIG. 1; and,

FIG. 6 is a bottom plan view of the low bay luminaire illus-
trated in FIG. 1.

The broken lines depict elements of the low bay luminaire
that do not form a claimed feature of the present invention.
